UNITED STATES PATENT OFFICE.

ADOLPHUS PAGE, OF TORONTO, ONTARIO, CANADA.

BALLOT-BOX.

No. 927,068.

Specification of Letters Patent.

Patented July 6, 1909.

Application filed January 27, 1909. Serial No. 474,532.

To all whom it may concern:

Be it known that I, ADOLPHUS PAGE, a citizen of the United States, residing in the city of Toronto, in the county of York, in the 5 Province of Ontario, Canada, have invented a new and useful Improvement in Ballot-Boxes, of which the following is a specification.

My invention relates to a ballot box 10 adapted to be used by secret societies for the purpose of balloting for candidates and other matters in connection with lodges and societies, in which the box is passed around the room whereby the different members may 15 readily obtain a ballot ball therefrom, and cast it therein, in a manner that those near him may not see the color of the ballot ball he deposits in the section of the box provided for that purpose.

20 The ballot box is so constructed that it comprises two essential parts in combination, one a receptacle for containing ballot balls, and the other an indicating receptacle. The ballot indicating receptacle is provided with 25 a transparent or glass inclosed front, with a hinged cover for same. The ballot ball receptacle is situated at the back part of the ballot box, and is also provided with a hinged cover. The ballot balls may be obtained 30 from the ballot ball receptacle, and deposited in the indicating receptacle, where they may readily be seen through the glass front, by raising the hinged cover, when the exact 35 number and species of ballot balls deposited therein may be counted and inspected, for the purpose of deciding the result of the vote.

The ballot indicating receptacle in the box 40 is an inclined front of the box inclosed by a glass plate or other transparent material, and the bottom is hinged to a cover, hinged to the back of the box and adapted to cover the ballot balls within the ballot ball receptacle, a section divided off in the bottom part of the box, when the ballots are not in 45 use. When the cover of the ballot ball receptacle is raised to permit the ballot balls being obtained the bottom of the ballot indicating receptacle closes up so that the ballot balls may be retained until the result of the 50 vote has been decided.

The design of the box as illustrated here- 55 with may be considerably varied as to the shape of the sides and length and breadth, but the essential features lie in the manner of arranging above a ballot ball receptacle, the ballot indicating receptacle with a dis-

appearing bottom to release the ballot balls into the ballot ball receptacle from where they were originally obtained, practically, without moving the ballot balls from the 60 box.

Figure 1 is a perspective front view of the ballot box; Fig. 2 is a perspective rear view of the ballot box; and Fig. 3 is a vertical sectional view through the box.

Like letters refer to like parts throughout the drawings and specification.

a—a are the sides and *b* the bottom of the box.

c indicates the ballot ball receptacle situated in the bottom of the box partially closed over by a dividing wall *d*. Closing over the other part of the ballot ball receptacle is a hinged cover *e*, adapted to be raised up and fastened in its raised position to expose the 75 ballot balls, and to permit them being obtained.

The ballot indicating receptacle *f* consists of an inclined back wall *g* and a glass front *h* relatively situated away from the back wall 80 *g* to leave a space *i* the width of the diameter through one of the ballot balls.

j designates the top of the ballot indicating receptacle, and formed through the top and adapted to communicate into the space 85 *i* between the back wall and glass front of the receptacle is a circular opening *k* sufficiently large to admit the insertion of a ballot ball.

l designates a division wall extending between the two sides *a—a* and adapted to 90 divide the ballot box into the front and back halves. Hinged to the front face of the division wall *l* and adapted to close over the glass front and ballot indicating receptacle is a cover *m*, adapted to prevent the 95 ballot as being cast from being seen, until the proper time when the officers of the lodge may raise the cover for that purpose. The cover *m* not only hides the ballot balls from being seen as they are being cast, but 100 also protects the glass front. The space *i* formed by the back wall and glass front communicates directly with the ballot ball receptacle *c* situated in the bottom of the box, through an opening *n* formed through 105 the dividing wall *d*.

Pivoted to the inner faces of the sides *b* of the ballot box are lever arms *o*, and supported on the outer ends of the lever arms is the removable bottom *r* of the ballot indicating receptacle.

p designates link arms adapted to pivot-

ally connect the lever arms *o* with the hinged cover *e*, that when the hinged cover is raised or lowered the lever arms will raise and lower with it. When the hinged cover *e* 5 is raised into a vertical position it opens up the ballot ball receptacle, and also raises up the outer end of the lever arm which carries with it the removable bottom *r* fastened to the outer ends of the lever arms and forces 10 it into the opening *n* in the ballot ball receptacle, and provides a bottom to support the ballot balls in between the inclined back and the glass front. Connected to the top edge 15 of the inclined back wall *g* is a catch *s* adapted to be fastened over the edge of the hinged cover *e* when raised into a vertical position to hold it in that position, that the removable bottom will be maintained in position to retain the ballot balls within the 20 ballot indicating receptacle when being inserted through the opening *k* through the top *j*.

When it is desired to release the ballot balls from the ballot indicating receptacle 25 and to destroy the ballot cast, the catch *s* is released from the edge of the hinged cover *e*, and allows the cover to be lowered into a horizontal position, and lower with it the lever arms *o*, which carry with them the removable bottom *r* away from the opening *n*, and allow the ballot balls to pass through the opening *n* into the ballot ball receptacle *c*.

Fastened to the top edge of the division 35 wall *l* is a handle *t* adapted for the purpose of carrying the ballot box around the room and to facilitate in presenting it to the voters for the purpose of obtaining and casting a ballot ball. Removably attached to the division 40 wall at a slight distance above the top *j* is a shield *u*, adapted to hide the view of the opening *k* in the top *j* into the ballot indicating receptacle from being seen by the person carrying the ballot box.

45 The sides *a*—*a* of the ballot box are adapted to extend rearward from the division wall sufficiently far to prevent persons on either side of the person casting their ballot ball seeing the color of the ballot ball used.

50 In Fig. 3 of the drawings I show in dotted lines the front cover *h* in a raised position to expose the condition of the ballot balls in the ballot ball receptacle. The hinged cover *e* is also shown in dotted lines in its open or 55 vertical position.

What I claim as new and desire to secure by Letters Patent is:—

1. In a ballot box, a ballot ball receptacle in the bottom of said ballot box, a hinged 60 cover forming the top of said ballot ball receptacle, an inclined ballot indicating receptacle extending upwardly from said ballot ball receptacle, an opening through the top into said ballot indicating receptacle, an ad-

justable bottom supported by lever arms, 65 said lever arms pivoted to the said hinged cover of said ballot ball receptacle, said adjustable bottom adapted to open and close communication between the said ballot indicating receptacle and said ballot ball receptacle, substantially as specified. 70

2. In a ballot box, a ballot ball receptacle, situated in the bottom of said ballot box, a hinged cover forming the top of said ballot ball receptacle, an inclined ballot indicating 75 receptacle situated above and adapted to communicate with said ballot ball receptacle, an opening through the top into said ballot indicating receptacle, a glass front for said ballot indicating receptacle, a hinged cover 80 adapted to close over said glass front, an adjustable bottom for said ballot indicating receptacle, said adjustable bottom supported on lever arms, said lever arms pivotally connected with the said hinged cover of said ballot ball receptacle, said adjustable bottom adapted to open and close communication 85 between said ballot indicating receptacle and said ballot ball receptacle by the raising and lowering of said hinged cover of said ballot ball receptacle, substantially as specified. 90

3. In a ballot box, a ballot ball receptacle situated in the bottom of said ballot box, a hinged cover for said ballot ball receptacle, an inclined ballot indicating receptacle situated above said ballot ball receptacle, an opening through the top into said ballot indicating receptacle, a glass front in said ballot indicating receptacle, a hinged cover adapted to close over said glass front, a removable 100 shield situated above said opening into said ballot indicating receptacle, a carrying handle fastened along the top edge of said ballot box, an adjustable bottom adapted to open and close communication between said ballot 105 indicating receptacle, and said ballot ball receptacle, substantially as specified.

4. In a ballot box, a ballot ball receptacle situated in the bottom of said ballot box, a ballot indicating receptacle, having a glass 110 front situated above said ballot ball receptacle, an opening through the top into said ballot indicating receptacle, a removable shield situated above said opening into said ballot indicating receptacle, a carrying handle fastened along the top edge of said ballot 115 box, an adjustable bottom adapted to be adjusted to open and close communication between said ballot indicating receptacle and said ballot ball receptacle, substantially as specified. 120

Signed at Toronto, this 8th day of January, 1909.

ADOLPHUS PAGE.

In the presence of—
JENNIE DERRETT,
A. A. ADAMS.
